COATING METHOD AND APPARATUS

John D. Murray and Russ B. Leech, Chicago, Ill.; said Murray assignor to The Liquafilm Corporation, Chicago, Ill., a corporation of Illinois; said Leech assignor to Standard Process Corporation, Chicago, Ill., a corporation of Delaware

Application March 6, 1939, Serial No. 260,188

10 Claims. (Cl. 91—33)

This invention relates to methods and apparatus for coating surfaces of sheets, webs or the like and is more particularly concerned with methods and apparatus for applying coating material upon such surfaces to obtain a uniform finish thereon.

In coating such sheet or web surfaces, the invention involves novel methods and apparatus for applying a uniform deposit of coating material thereon. It is immaterial to the practice of the invention whether these materials lie wholly on the surface to be treated or partially or wholly impregnate the surface.

The disclosure of a preferred embodiment of the invention in the present instance will be specifically directed toward the coating of sheet or web surfaces with plastic coating materials which are normally solid, such as solid lacquers, or resins which are melted for application to the sheet surface, although the invention is not so limited.

Coating methods and apparatus in general use today for applying surface coatings of liquids and similar materials to sheets or webs have not proved successful for applying smooth coats of melted plastic material to sheet or web surfaces. These plastic materials harden almost instantly when they are deposited upon the sheet surface and attempts to spread these coatings during and after deposit have resulted only in incomplete, non-uniform streaky and uneven coatings.

Moreover, these present day coating methods are relatively slow and afford no measured or accurate control over the amount of coating material actually deposited on the surface.

With these defects of the prior art in mind, it is a major object of the present invention to provide a novel method and apparatus for speedily applying accurately measured and controlled quantities of coating material upon a sheet or web surface in a uniform coating.

A further object of the invention is to provide a novel method and apparatus for coating a sheet surface which comprises progressively passing a sheet, upon a surface of which coating material has been deposited, over a smooth even face, or a plurality of smooth even faces in succession, under tension or pressure and then contacting the coated surface with a smooth flexible straight edge, at an angle selected to give a predetermined finish to said surface. In its preferred embodiment, suitable adjustments are provided for determining the area of contact between the coated sheet or web surface and the smooth face, and for determining the angle at

the straight edge. Also provision is made for applying heat to the coated surface while in contact with the smooth face. Preferably the straight edge is provided at the termination of a smooth even flexible face member loosely supported adjacent one end and overlying a smooth relatively rigid backing member. Usually the sheet or web is maintained under tension during this treatment.

A further object of this invention is to provide a novel method and apparatus for coating a sheet surface or the like wherein controlled quantities of coating material are deposited upon the surface, and subjected to sufficient pressure and heat, by special smoothing apparatus, to fuse the deposited material into a smooth, uniform coating. In the preferred embodiment, the deposited material is a melted thermo-plastic deposited upon the surface by a special grooved roller and the fusing temperature must be at least as high as the temperature of the melted thermo-plastic when it was deposited.

A further object of the invention is to provide a novel coating material depositing roller having either a plurality of fine, closely adjacent surface grooves, or uniformly spaced pockets, of uniform predetermined depth and width.

A further object of the invention is to provide a novel apparatus and method of coating and glossing or finishing a sheet surface with thermo-plastic material wherein the sheet, upon a surface of which the material has been deposited, is progressively drawn under tension over a smooth heated face with its uncoated side in contact with said face over a substantial area and then the coated surface of the sheet is passed over a smooth flexible straight edge at an angle selected to give a predetermined finish to said surface. If desired, the coated surface of the sheet may be exposed to additional heating means such as a radiant heater as it passes over said surface and the straight edge is preferably automatically maintained at a predetermined high temperature.

Further objects of the invention will presently appear as the description proceeds in connection with the appended claims and the annexed drawings in which:

Figure 1 is an end elevation of a coating apparatus for carrying out one embodiment of the invention.

Figure 2 is a side elevation of the special coating depositing roller of the invention with a section of its peripheral surface greatly enlarged to illustrate the groove formation.

Figure 3 is a fragmentary sectional view of a portion of the coating roller of Figure 2 greatly enlarged and illustrating further the surface groove formation.

Figure 3A is a section of a portion of the sheet illustrating the manner in which the coating material is deposited upon the sheet surface prior to the smoothing operation.

Figure 4 is a fragmentary view of the surface of a further embodiment of the coating roller illustrating a series of surface pockets defining a grid pattern.

Figure 5 is an end elevation illustrating another embodiment of the coating and finishing apparatus of the invention wherein the glazing blade is separate from the smoothing surface which contacts the uncoated surface of the sheet.

Figure 6 is a somewhat diagrammatic view of still a further embodiment of the coating and smoothing apparatus of the invention wherein the uncoated web surface is backed by a cylindrical roller.

Figure 7 is a somewhat diagrammatic view illustrating a further embodiment of the coating and smoothing apparatus which is especially adapted for relatively high sheet or web speeds.

Figure 8 is an exploded view in section illustrating an insulated glazing blade holder.

Figure 9 is a fragmentary sectional view of a notched bar for wiping a smooth surfaced coating roller.

Figure 10 is a fragmentary front elevation in section illustrating further the blade of Figure 9.

Referring to Figure 1, a heavy base 11 is provided with a vertical front frame member 12 and a pair of rear corner posts 13 joined by a horizontal apron 14. A pair of horizontal frame end members 15 extend from posts 13 to the bottom of the intermediate vertical frame portions 16 and a top frame member 17 connects front member 12 and intermediate frame portions 16.

Preferably base 11 and frame members 12-17 comprise an integral heavy casting having sufficient weight and rigidity to withstand vibration due to the driving mechanism.

Coating deposit apparatus

Each frame end member 15 is recessed at 18 to receive a bearing support 19 removably secured to member 15 by bolts 21. Each support 19 carries a journal 22 for end shafts 23 of a grooved coating roller 24.

A plate 25 is pivoted at 26 on each support 19 and liquid tight sealing shoes 27 extend from each plate 25 to shafts 23. An idling roller 28 is supported by webs 25 with its cylindrical surface in substantial contact with the surface of roller 24 for a purpose to be later described.

A container 29 is adjustably pivoted on rod 31 to vary the level of the coating solution. The free side of container 29 is provided with a projecting rotatable pin 32 resting in slot 33 formed at one end of rock lever 34 fixed to pivotal shaft 35.

Shaft 35 is rigid with a crank 36 having an elongated angularly disposed handle 37. Referring to Figure 1, rotation of handle 37 in a clockwise direction will cause rotation of shaft 35 and lever 36 in the same direction to raise container 29. Rotation of handle 37 in a counterclockwise direction lowers container 29. Shaft 35 is journaled in a suitable rigid extension from the frame (not shown).

Container 29 is provided with any suitable heating means controlled to maintain the coating

fluid at a desired temperature. Since the invention is not concerned with the specific type of heater construction, further description of it is not necessary to understand the invention. A suitable drain plug 38 is provided at the bottom of container 29.

A door 39 of container 29 may be opened for access to the coating roller. Suitable end walls on container 29 retain the coating liquid and are preferably in fluid tight connection with shafts 23 to prevent the fluid from escaping to the bearings in journal 22. These fluid tight connections are designed to permit the above described adjustments of the container.

Each frame portion 16 is provided with an angular projection 41 forming a slide guide 42 supporting slide blocks 43 for rotatably and adjustably supporting opposite end shafts 44 of bifurcated doctor blade support 45.

A doctor blade holder 46 is removably secured between the arms of support 45 by screws 47 or similar releasable fastening elements. Doctor blade holder 46 comprises a pair of rigid bars clamped along one end of the doctor blade. The doctor blade includes a relatively stiff blade 48 of sheet steel or the like serving as a backing for a flexible blade 49 of spring steel, or some material having similar properties, which extends substantially parallel to the axis of cylinder 24 and bears in wiping engagement with its cylindrical surface along its entire length.

A handle 51, rigidly secured to blade support 45, regulates the pressure of blade 49 upon the surface of cylinder 24. When handle 51 is pushed downwardly in Figure 1, blade support 45 is rocked counterclockwise about shafts 44 to ease the pressure of blade 49 on cylinder 24. Movement of handle 51 in the opposite direction increases the pressure of blade 49 on the surface of cylinder 24.

A brace 52 on projection 41 is provided with a threaded bore 53 for receiving a threaded portion of a doctor blade adjustment rod 54 having a handle 55. Rod 54 is formed with a rotatable bearing portion which extends through block 43 and terminates within a recess 56 in block 43.

Collars 57 and 58, secured to rod 54 by suitable means such as pins 59 and 61, abut adjacent edges of block 43 and recess 56. When handle 55 is rotated, rod 54 is displaced longitudinally and block 43 is thereby displaced along its guide 42.

The above described doctor blade adjustments are provided for correctly aligning the doctor blade with the cylindrical coating surface and for varying the angle and pressure of the blade at that surface.

The doctor blade is heated by any suitably controlled heating means (not shown).

The web S to be coated is led over the top of roller 24 tangentially to its cylindrical surface, being guided by idler rolls 62 and 63 journaled in suitable bearings in frame members 64.

An impression roller 65, the cylindrical surface of which is preferably covered with a resilient blanket of rubber or some suitable material, is mounted for rotation in vertical axial alignment with the coating roller.

End shafts 66 of roller 65 are journaled in bearings 67 on slide blocks 68 and a removable cap 69 is secured upon each bearing by screws 71. Each block 68 is slidably supported upon a vertical guide 72 on frame members 16.

An integral boss 73 on each block 68 rotatably carries the lower end of impression roll adjustment rod 74. Collars 75 and 76, secured non-

rotatably upon rod 74 at opposite sides of boss 73 by pins 77 and 78 respectively, prevent axial displacement of rod 74 with respect to boss 73 when rod 74 is rotated.

Each rod 74 is threaded above collar 75 and passes through a cooperating threaded bore in a boss 79 formed in a bracket 81 rigidly secured to frame member 16 by a plurality of bolts 82. A bevel gear 83 is secured to the upper end of each rod 74 and each gear 83 meshes with a suitable bevel gear 84 on transverse shaft 85. Hand-wheels 86 are fixed to opposite ends of shaft 85.

Shaft 85 is rotatably supported upon the frame in any suitable manner and may be provided with suitable locking means for preventing accidental rotation.

When either handwheel 86 is rotated, rods 74 are displaced vertically to shift blocks 68 along guides 72 and to effect vertical adjustment of the whole impression roller 65.

Coating roller

Roller 24 is preferably made of steel and is accurately ground to form a true cylindrical surface 87. By means of a special milling tool, a plurality of closely adjacent, fine line grooves 88 are cut into surface 87. These grooves 88 are parallel and are inclined sufficiently to allow the outer plane surface of the cylinder to be wiped clean by doctor blade 49. They may be disposed at from 10 degrees to 80 degrees but preferably are disposed at about 45 degrees to the axis of the roller and are of uniform depth and shape so as to contain the same amount of coating material.

The size and spacing of the grooves is varied in accordance with the nature of the materials and the amount to be deposited per unit of area. The ratios of line width to groove width are such that sufficient area is provided on the raised surfaces or lines so no embossing of the web or sheet to be coated occurs under the pressure required to assure satisfactory drawing of the coating material from the grooves or pockets. The grooves may be arranged at any angle with the cylinder axis but should be disposed at such an angle with respect to the edge of the doctor blade that proper wiping of the plane surface of the cylinder is assured. For uniform deposit of thin coatings, it is essential that all of the grooves be of uniform depth in order that each shall deposit the same amount of material. For this reason the roller surface is cut by a specially designed milling tool so that the exact dimensions of each groove can be accurately determined. Since the grooves can be cut to uniform depth and known dimensions accurately, the quantity of coating material deposited on the sheet surface is accurately measured and controlled.

A practical coating roller, which has been used with success for depositing melted solid lacquer at a rate of 5.1 pounds per 3000 square feet of sheet surface, has its grooves cut exactly at 45 degrees to the cylinder axis, and these grooves are equally spaced and to the order of 34 grooves per inch. Each groove is .001 inch deep, and the wall between grooves is one-third the width of the groove.

While for some purposes grooves 88 may be formed by acid etching, this method has been found unsatisfactory because the etching process does not afford sufficiently accurate control over the depth and other dimensions of the grooves.

It will be further understood that the surface grooves on roller 24 may be formed by electro-

deposition or built up in some other manner upon the cylindrical surface.

When it is desired to accurately deposit a coating of given thickness upon a sheet surface, a roller having its surface milled to provide grooves of suitable depth and size is selected or prepared for the job at hand.

A modified form of roller surface is illustrated at 91 in Figure 4 wherein the roller surface recesses comprise uniform pockets 92, milled into the roller surface by special milling tool to produce a grating or screen effect at the roller surface. In this modification the cylindrical roller surface appears as a plane surface 93 into which pockets 92 are cut.

While the coating roller surfaces have been disclosed as having deposited recesses on their entire periphery it will be understood that spot coating may be effected by forming the depositing recesses at any desired area or spaced areas around the periphery of the cylinder. Cross-reference is hereby made to the co-pending application of Russ B. Leech Serial No. 272,526, filed May 8, 1939, wherein this deposit roller per se and the method of making it are claimed.

Coating and finishing apparatus

After leaving the coating station the sheet passes to a leveling and smoothing station as illustrated in Figure 1.

A supporting frame portion 90 extends upwardly from each frame end member 15. Each frame portion 90 is formed with an inwardly extending hollow lug 90' through which extends a rod 100 having enlarged annular collars secured non-rotatably thereto at opposite ends of lug 90'. An operating handle 94 is rigid with the upper end of each rod 100.

The lower end of each rod 100 is threaded within bore 95 which is preferably integral with a slidable frame member 96 mounted in slide guides 96'. Frame members 96 are rigid with opposite ends of a quadrant-shaped shoe 97 having a smooth curved surface 98 which is preferably chromium plated and polished highly for the sake of hardness and smoothness.

Each frame member 96 carries a slidable block 99 having a threaded bore for receiving the lower threaded end of an adjustment rod 101 at whose upper end is an enlarged rigid handle 102. Each rod 101 is rotatably supported in a bore in a ledge 103 preferably integral with each member 96, and is prevented from vertical displacement therein when rotated.

A wide flexible glazing blade 104, preferably of thin sheet doctor blade steel, of from .005 to .020 of an inch thick, and which may be tapered at its free end if desired, has one edge loosely held between a pair of bars 105 and 106 by screws or bolts which pass through holes in the blade of larger diameter to permit heat expansion. Preferably the bars of 105 and 106 are of heat insulating material, or heat insulated. If this edge is tightly clamped, the blade 104 will warp when the necessary heat is applied thereto and will not present a smooth straight free edge in contact with the coating material.

The opposite ends of bar 106 are secured to blocks 99 so that blade 104 is coextensive with surface 98.

Blade 104 extends upwardly from its support at a tangent to the lower edge of surface 98 and extends over surface 98 in contact therewith. Since blade 104 is generally too thin and flexible to support itself in an upright position, it is

effectively supported medially by surface 98, which stops short of the free edge of the blade. In practice a projection of one quarter of an inch of free edge of blade 104 beyond the medial support, has given excellent results. This projection gives sufficient flexibility of support to the free blade edge to maintain it in contact with the surface under treatment, regardless of variations in tension along the surface, and regardless of surface irregularities. This resilient flexing action of the blade in compensating for irregularities is plainly visible in operation.

A vibration restricting roller 108, whose end shafts 109 are supported rotatably in blocks 111 slidable upon frame member 96, has a continuous blanket of rubber or other resilient material at its peripheral surface for contacting the top surface of a sheet whose lower surface is contacted with blade 104.

Roller 108 extends along the whole length of surface 98 adjacent the free end of blade 104 and is adjustable toward and away from surface 98 along a line which is generally normal to a common tangent to surface 98 and roller 108.

Each frame member 96 is provided with a ledge 112 for rotatably supporting an adjustment rod 113 whose lower threaded end is received within a threaded lug 114 integral with block 111. An enlarged handle 115 and an enlarged portion 116 on rod 113 cooperate with opposite sides of ledge 112 to prevent vertical displacement of rod 113 when it is rotated.

Each frame member 96, beyond roller 108, is provided with a guide 117 within which is slidably received a block 118 rotatably supporting end shafts 119 of a vertically adjustable highly polished steel cylindrical roll 121.

An adjustment rod 122 threaded in a threaded bore in each block 118 is rotatably supported in a suitable ledge 123 integral with each frame member 96 and is prevented from axial displacement by cooperation of an enlarged operating head 124 and an enlarged portion 125 of rod 122 with opposite sides of ledge 123.

Beyond roll 121, an elongated, arcuate, smooth surfaced cooling member 126 is mounted upon the frame by suitable supports 127 and 128 rigid with boss 79 and frame member 17 respectively. The web contacting surface of member 126 is cooled by circulation of water or some other fluid. Any other suitable web surface cooling means may be used at 126.

Beyond the cooling member 126, which is provided to set the coating sufficiently to pass through draw rollers without injury, frame members 17 are provided with draw roll supports 129 supporting end shafts 131 of draw roll 132 which is driven by a suitable mechanism (not shown) in synchronism with the rewinding drive mechanism.

A pressure roller 133, parallel to roll 132, has its end shafts 134 rotatably supported in blocks 135 slidable vertically in guides 136 in each support 129. An adjustment screw 137 passing through a cooperating threaded bore in a ledge 138 on each support 129 has its lower end rotatably connected to block 135 so that, when screws 137 are rotated, roller 133 is vertically displaced.

Near the upper ends of frame members 12, aligned support brackets 139 are provided with slotted guides 141 for receiving end shafts 142 of a guide roller 143. Each end shaft 142 is rotatably connected to adjustment screws 144 co-

operating with suitable threaded bores in bracket 139 for vertically adjusting roller 143.

Operation of coating apparatus

The preferred embodiment of the invention is concerned with the coating of a continuous web surface with a thermo-plastic such as a normally solid solution.

The uncoated web S, which may be of paper or other fibrous material, is drawn from a supply reel over guide roller 143 downwardly to the coating deposit station where it is directed along the lower surfaces of idler rollers 62 and 63, the web is drawn through the pass defined by driven coating roller 24, and impression roll 65. As described above, roller 65 may be vertically adjusted toward and away from roller 24 to vary the pressure of the rollers upon the web surfaces.

When the material to be applied to the web surface is thermo-plastic, it is placed in pan 29 and heated so as to maintain it in a fluid state. The fluid coating material in the container is maintained at such a level that a substantial portion of the surface of roller 24 is always immersed. The supply of coating material may be replenished manually or automatically as desired and the latter operation is made possible by the fact that roller 24 deposits known measured quantities of coating material at a constant rate as will be described below.

As roller 24 rotates in a clockwise direction in Figure 1, surface grooves 88 become filled with coating material as they travel through the fluid bath. Coating material on the plane roller surface is wiped away by blade 49 and falls back into pan 29. Preferably the surface of roller 24 and the wiping blade 49 are thermostatically maintained at the same temperature as the coating material, or even slightly higher, so that the material will not harden and become accumulated upon either.

After passing doctor blade 49, the surface of roller 24 comprises a clean cylindrical surface 87 and a plurality of grooves 88 filled to the level of surface 87 with fluid coating material. The coating material is transferred to the under surface of web S at the pass defined by rollers 24 and 65 where surface 87 contacts the bottom web surface directly. The deposited coating material assumes the form of a plurality of uniform rows or ridges 89 lying upon the web surface as illustrated in Figure 3A.

If desired, the web surface may be pre-heated, but generally the web surface is substantially cooler than the coating material and most thermo-plastics solidify or thicken almost instantly upon contact with the web surface.

After passing the depositing station, web S passes through the smoothing station or stations with the coated web surface in full contact with a substantial area of blade 104. Since web S is tensed, blade 104 is forced into surface contact with the underlying heated arcuate face 98 so that the coated web surface passes over a heated, smooth, flexible arcuate face at this station.

The coating on the web is now subjected to a higher temperature than at the coating station because here the now partially solidified ridges of coating must be leveled off by heat and pressure in the very short period of time that the web passes over blade 104. This temperature varies in accordance with the nature of the coating material, and the time of contact of the material.

The area of contact between the coated web surface and the smooth face of blade 104 can be

varied by the adjustment controlled at 94 whereby member 97 is displaced vertically in a direction generally normal to the tensed web. Variation of the area of contact of the web and blade surfaces is effected in accordance with the speed of operation desired.

Excessive vibration, under certain conditions is prevented by roller 108 which urges the free end of the blade firmly toward the upper portion of face 98, and whose resilient surface helps absorb the minor vibrations set up in the blade.

The smoothed coated web surface is drawn downwardly over the straight smooth edge 107 of blade 104 at an angle selected to give the desired finish to the coating. This angle varies in accordance with the amount of coating material applied and should be such that the material leaves the blade edge without turbulence. For obtaining a high glossy finish upon a web coated with the thermo-plastic known as "Li-quafilm". Satisfactory results are obtained with the web disposed at an angle of from ten to twenty degrees with a tangent to the blade end. Web S, after passing edge 107, passes around the vertically adjustable roller 121 and thence upwardly along the cooling member 126 to the draw roll 132. The angle between web S with edge 107 is determined by the vertical position of roller 121.

After passing the draw roll, the coated web is rewound upon a suitable rewind apparatus (not shown) whose speed is automatically varied as the roll diameter increases. Roll 132 is driven at a constant speed sufficient to keep the web under a predetermined tension as it travels through the above described smoothing and glazing apparatus.

When a solvent lacquer or similar material which does not have to be melted to render it fluid for coating purposes is to be deposited upon the sheet or web surface, the grooved roller deposits that lacquer or material in a substantially even coating so that the above described heating and smoothing operation need not be performed, but the surface is drawn past the smooth flexible edge to give it the desired finish.

Modifications of Leveling and Finishing Apparatus

In the apparatus of Figure 5, roller 24 deposits a measured quantity of melted coating material upon the underside of web S in the manner above described and web S then passes directly over an arcuate shoe 145 with its uncoated side in full face engagement with the smooth, preferably chromium plated and polished, arcuate face 146 of the shoe.

Shoe 145 is provided with suitable heating means for maintaining face 146 at a temperature sufficient to soften the coating material as the web passes thereover. Opposite face 146, an auxiliary radiant heater 147, comprising a reflector 148 and a plurality of internal heater units, is pivotally supported at 149 upon a suitable frame member. Heat from heater 147 is directed upon the coated web surface by reflector 148 and the amount of that heat can be controlled either by varying the number of heating coils energized or the distance between reflector 148.

Preferably web S enters and leaves surface 146 substantially tangentially to reduce resistance to passage of the web. Just before web S leaves surface 146, the coated surface is engaged by a

straight, smooth edge comprising the free end of a flexible glazing blade 151 of the same material as blade 104. Blade 151 preferably contacts the surface of the web in such a manner that the edge is free from pressure on surface 146 as the web leaves it, the pressure on surface 146 being applied slightly back of the free blade edge.

Blade 151 is supported similarly to blade 104, having an edge loosely held between flat bars 152 and 153, preferably heat insulated, secured together and removably retained upon glazing blade support 154 by a plurality of screws 155. Cylindrical stubs 156 at opposite ends of support 154 extend into suitable journals in brackets 157 bolted or otherwise secured to rigid frame plates 158.

Preferably shoe 145 is rigidly supported in a suitable manner at opposite ends upon plates 158 which also support the heater pivots 149.

As above described, blade 151 is medially supported on surface 146 and is arranged at an acute angle to web S, and contacts the fluid coating material in wiping engagement so as to give it a desired finish. The projection of blade 151 beyond its medial support, and its angle with web S should be the same as described for blade 104 in Figure 1, for the reasons hereinbefore given.

When blade support 154 is adjusted in either direction about the axes of stubs 156 by an arrangement similar to that described for doctor blade 49 in Figure 1, the pressure of glazing blade 151 upon the web and the angle between web S and blade 151 are varied. This adjustment is made in accordance with different thicknesses and types of coating material as hereinbefore set forth.

Blade 151 is provided with electrical coils or other suitable heating means for thermostatically maintaining it at the proper temperature as described for blade 104.

Instead of using stationary heated shoes such as those at 97 and 145 the invention also contemplates the use of a rotatable heated shoe such as the roller 161 illustrated in Figure 6. Roller 161 has an accurately cylindrical, chromium plated, highly polished peripheral surface over a portion of which the web S passes after the coating material has been deposited thereupon.

Roller 161 is preferably provided with a variable speed drive mechanism (not shown) so that it can be driven in accordance with desired web speeds.

After passing roller 63 web S extends along the lower surface of a vertically adjustable roller 162 whose ends are journaled in blocks 163 slidable in guides 164 in opposed rigid frame members 165. Suitable adjustment screws 166 threadedly engaged with a ledge 167 on each member 165 and rotatably connected to each block 163 provide for vertical displacement of roller 162. When roller 162 is displaced downwardly it strips a portion of the web off the surface of roller 161 to vary the amount of heat applied to the web coating in accordance with the nature of the coating material and the speed of the web.

The uncoated surface of web S is wrapped in contact with heated roller 161 and the coated surface of web S is contacted by the adjustable glazing blade 151 at substantially the same angle as described above in connection with Figure 5. Similarly the auxiliary heater unit 147 directs heat upon the coated surface of web S as it passes along the roller 161. Roller 161 is preferably

heated by suitable internal units or the like in the same manner as roller 24 above described.

The apparatus illustrated in Figure 7 is a later improved development for high speed production.

The web S passes over a series of flexible smoothing and glazing blades 168, each loosely held in the manner of blade 104, between heat insulated bars 169 and 169', adjustably pivotally mounted upon frame portions 170. These blades are of the same material and thickness, and function the same as blades 104 and 151 hereinbefore described. The blades are supported medially and heated by the curved heated bars 171, also mounted on frame portions 170, and against which they are flexed or bent by the tension of web S in passing between rollers 172, and over the free flexible edges of the blades. Each bar 171 is provided with a separate automatic temperature control. A roller 173, mounted for horizontal adjustment in any suitable manner, is provided to control the angle at which the web leaves the free flexible edge of the upper blade 168. The frame portions 170 supporting bars 171 and blades 168 are also adjustably mounted to vary the area of contact between the coated web surface and the flexed blade portion and to vary the pressure at that area of contact.

When frame portions 170 are adjusted to the right in Figure 7, each adjacent blade 168 is then adjusted slightly counterclockwise about its pivot to insure that its free edge is raised from contact with the surface of bar 171. Otherwise the coated surface might contact the hot bar 171 after passing the glazing blade edge and the finish of the coating would be destroyed.

Frame portions 170 are all supported upon an elongated frame member 175 pivotally connected at 176 to the stationary frame bed which carries rollers 172, so that all of the glazing blades may be simultaneously swung to one side to thread the web, or gain access to the rollers and blades.

After passing over roller 173, the uncoated surface of web S is drawn over one or more cooling rollers 174 which set the deposited and glazed film so that it may pass through drawing rollers without injury.

As the coated web passes over heated blades 168, sufficient heat and pressure is imparted to the coating at each blade so that the solidified ridges or mounds 89 are successively softened and leveled off as shown schematically in Figure 7, without raising the temperature of the coating to such a point that it will be removed by the blades. When the coated web reaches upper blade 168 the ridges should be completely leveled, so that this blade need merely glaze the coated surface or film.

It will be noted that in this embodiment of the invention, heat is applied only to the coated side of the sheet, thus carrying out the coating operation without materially changing the moisture content of the sheet, and if desired the back of the sheet may be cooled during the smoothing and glazing operation.

Insulated blade holder

An insulated blade holder which may be used for supporting a blade 168 of Figure 7 is illustrated in Figure 8, wherein bars 177 and 178, provided with inner facings 179 and 181 respectively of a suitable heat resistant material, such as Bakelite, are adapted to be drawn together upon opposite sides of blade 168 by suitable screws

passing through aligned apertures 182 and 183 in the respective bars.

A series of integral alignment pins 184 extend from bar 178 through aligned apertures 185 in bar 177 after passing through suitable apertures 186 in blade 168 which are appreciably larger than the pins to permit free expansion of the heated blade and prevent warping of the flexible edge as above described.

The insulated holder of Figure 8 is especially useful for holding thin blades which would warp excessively in an ordinary metal holder due to widely different temperature levels in different areas, and the blades are loosely held at one end just as are blades 104 and 151 above described.

Modified coating device

Accurately measured quantities of coating material may be deposited from a smooth surfaced cylindrical coating roller by wiping the surface with a uniformly notched wiping bar, which is preferably reciprocated slowly to avoid wearing grooves into the roller surface and leaves the coating material in spaced ridges at the point of transfer to the sheet or web surface.

A preferred form of this apparatus is illustrated in Figures 9 and 10 where a cylindrical, smooth surfaced coating roller 187, rotating in a suitable coating bath, is engaged along its entire length by a flexible spring steel bar 188 supported by a suitable holder 189. As illustrated in Figure 10, bar 188 is generally wedge-shaped in cross section and extends through a suitably formed slot or socket in holder 189, to contact the surface of roller 187. At spaced points along bar 188, it is engaged by resilient backing assemblies, each comprising a washer 191 directly engaging the bar, a coil spring 192, a second washer 193 and an adjustable screw 194 threadedly engaging washer 193 and an end wall of holder 189.

The wiping face of bar 188 is arcuate in section so as to provide substantially line contact between the bar and roller and is notched uniformly, with the size and spacing of the notches of the same order as the size and spacing of the grooves in the grooved coating roller above described. Between each notch 195 is a tooth 196 which bears in wiping contact with the cylindrical surface of roller 187 as illustrated in Figure 10.

As roller 187 rotates clockwise in its bath in Figure 10, its smooth cylindrical surface becomes covered with coating material which is removed in longitudinally spaced bands by teeth 196 as the surface traverses the wiping blade. After passing the wiping blade, the coating roller surface contains a series of longitudinally spaced rows or ridges of coating material of uniform size which are transferred to the under surface of web S at the pass defined by roller 187 and an impression roller such as that illustrated at 65 in Figure 1.

Holder 189 is preferably rigidly mounted upon the frame so that teeth 196 are in proper wiping contact with the roller surface and movement of bar 188 toward the roller surface is limited by its engagement with its socket on holder 189. Any desired number of the above described resilient backing assemblies may be provided along bar 188 and each is separately adjustable to locally vary the pressure on the bar or compensate for warping of the bar. The above described resilient mounting of the bar permits it to flex and glide over solid impurities which otherwise might destroy teeth 196 if the bar were rigid.

Uniform reciprocation of the bar 188 longitu-

dinally of the roller surface may be effected by any suitable means such as those now in use for similarly reciprocating ink doctor blades on printing press inking rollers.

The fundamental aspects of the above-described process and apparatus, comprising depositing measured spaced quantities of coating material on a surface to be coated, employing a flexible smoothing face for leveling the deposited quantities, and drawing the coated surface over a flexible edge at a selected glazing angle, are the sole invention of John D. Murray and are claimed broadly and specifically in his co-pending application, Serial No. 313,135, filed January 9, 1940, to which cross-reference is hereby made.

This invention may be embodied in other specific forms without departing from the spirit or essential characteristics thereof. The present embodiments are therefore to be considered in all respects as illustrative and not restrictive, the scope of the invention being indicated by the appended claims rather than by the foregoing description, and all changes which come within the meaning and range of equivalency of the claims are therefore intended to be embraced therein.

What is claimed and desired to be secured by United States Letters Patent is:

1. The method of uniformly and smoothly leveling coating material over a sheet surface or the like upon which it has been deposited in ridges or mounds, which comprises the steps of drawing said coated surface successively over a plurality of spaced, stationary, smooth faces, and then contacting said coated surface with a straight smooth edge at an angle selected to give a glazed finish to said surface.

2. Apparatus for smoothing and glazing a sheet or like surface coated with uniform spaced quantities of thermoplastic coating material comprising a plurality of smooth, heated, flexible blades with which said surface is successively contacted under pressure to smooth said spaced quantities into an even film, the final blade terminating in a free straight flexible edge over which said surface is drawn at a selected angle to impart a desired glaze or finish to said film.

3. In apparatus for evenly and smoothly leveling coating material which has been deposited upon a sheet surface or the like, a plurality of stationary members having smooth surfaces over which the coated surface is drawn in succession, means for imparting heat to said coated surface at each of said members in such a manner that the material on said coated surface is smoothed out gradually as the surface passes successively over said members, and means for subsequently contacting said coated surface with a smooth straight edge at an angle selected to give a glazed finish to said surface.

4. The apparatus defined in claim 3, together with means for varying the area of contact between said coated surface and said members.

5. Apparatus for uniformly leveling coating material which has been deposited upon a surface of a sheet or web in ridges or mounds comprising a member having a rigid smooth face and a flexible, web surface contacting element loosely supported at one edge adapted to overlie said smooth face; means for passing said web under tension in contact with a predetermined end area of said web contacting element, and means for adjusting said member to determine the area of contact between said web and said end area of said element.

6. The method of uniformly and smoothly leveling coating material over a sheet surface or the like upon which it has been deposited in measured quantities, which comprises the steps of drawing said coated surface successively over a plurality of spaced, stationary, smooth flexible faces to gradually level said deposited coating, and then contacting said coated surface with a straight smooth flexible edge on the final face at an angle selected to give a glazed finish to said coated surface.

7. In apparatus for uniformly and smoothly leveling coating material which has been deposited in spaced quantities upon a sheet or like surface, a guideway over which said sheet passes with said deposited coating facing outwardly; smoothing mechanism comprising a plurality of spaced flexible blades over which said surface is successively drawn under pressure, each blade being supported along one edge and having a smooth face contacting said deposited coating, and an arcuate backing for each blade designed to support and control the curvature of each said blade as it bends in response to pressure of said sheet; and a movably mounted support for said smoothing mechanism for bodily and simultaneously shifting all of said blades into or out of engagement with said sheet surface.

8. In the apparatus defined in claim 7, said guideway being supported on a stationary frame, and said smoothing mechanism support comprising a frame member pivotally mounted on said frame.

9. In the apparatus defined in claim 7, said guideway comprising a plurality of spaced rollers, and said flexible blades being spaced to engage said surface between adjacent rollers.

10. In the apparatus defined in claim 7, the backing for each blade comprising a rigid non-rotatable bar extending parallel to said blade, and means for shifting each blade and associated bar as a unit toward or from said guideway.

RUSS B. LEECH.
JOHN D. MURRAY.
